(57) **CLAIM**

The ornamental design for an assembling game plate, as shown and described.

DESCRIPTION

FIG. 1 is a front view of an assembling game plate of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a sectional view thereof taken along the line 8-8 of FIG. 1; and,

FIG. 9 is a sectional view thereof taken along the line 9-9 of FIG. 3.

The broken lines are for the purpose of illustrating portions of the article that form no part of the claim.
